CLAIM

The ornamental design for a lawnmower, as shown and described.

DESCRIPTION

FIG. 1 is a front view of a lawnmower;
FIG. 2 is a rear view of the lawnmower;
FIG. 3 shows a first side view of the lawnmower;
FIG. 4 shows a second side view of the lawnmower;
FIG. 5 is a top view of the lawnmower;
FIG. 6 is a bottom view of the lawnmower; and,
FIG. 7 is a perspective view of the lawnmower.
The portions of the article shown in broken lines do not form part of the design.

1 Claim, 5 Drawing Sheets(56)
